CLAIM

I claim the ornamental design for a writing instrument grip, as shown and described.

DESCRIPTION

FIG. 1 is a front view showing my new design for a writing instrument grip.

FIG. 2 is a front view showing the grip of FIG. 1 applied to a writing instrument.

FIG. 3 is a perspective view of the writing instrument of FIG. 2.

FIG. 4 is a bottom view of the grip of FIG. 1 applied to a tri-lobal writing instrument body.

FIG. 5 is a bottom view of the grip of FIG. 1 applied to a circular writing instrument body; and,

FIG. 6 is a bottom view of the grip of FIG. 1 applied to an octagonal writing instrument body.

In FIGS. 1-6, the broken lines are for purposes of illustration only, and do not form a part of the claimed design.
